(57) **CLAIM**

We claim the ornamental design for a UICC apparatus, as shown and described.

DESCRIPTION

FIG. 1 is a plan view of a UICC apparatus; FIG. 2 is a front view of the UICC apparatus of FIG. 1; FIG. 3 is a right side view of the UICC apparatus of FIG. 1; FIG. 4 is a left side view of the UICC apparatus of FIG. 1; and, FIG. 5 is a rear view of the UICC apparatus of FIG. 1. Broken lines and portions contained within broken lines are not claimed.
